UNITED STATES PATENT OFFICE.

ADRIAN ST. C. GARMAN, OF PHILADELPHIA, PENNSYLVANIA.

BEDSTEAD.

1,258,556.

Specification of Letters Patent.

Patented Mar. 5, 1918.

Application filed May 3, 1916. Serial No. 95,260.

To all whom it may concern:

Be it known that I, ADRIAN ST. CLAIR GARMAN, a citizen of the United States, residing at Philadelphia, in the county of Philadelphia and State of Pennsylvania, have invented new and useful Improvements in Bedsteads, of which the following is a specification.

The invention relates to beds, and more particularly to bedsteads, and has for an object to provide an extension bedstead that can be quickly and conveniently changed from a single to a double bedstead and which in either its normal single bedstead 10 position or in its extended position will present a neat and effective appearance and not divulge to the casual observer that it can be changed from a single to a double bedstead or vice versa.

20 The invention comprehends among other features the provision of a bedstead which in view of its novel construction and arrangement will be strong and durable and cannot readily get out of order and which 25 furthermore on account of the simplicity of the construction can be readily cleaned and kept in sanitary condition.

Still further objects of the invention reside in a bedstead which, aside from being 30 supported by the usual four posts, forming a part of the construction, will be supported by additional uprights or auxiliary legs when the bedstead is in its extended or open position, the head and foot boards further- 35 more being so formed and arranged with respect to the head and foot posts that the bedstead when in normal or extended position will appear as any other rigid form of bedstead, single or double, and not capable 40 of being extended from its single to a double bedstead or vice versa.

In the further disclosure of the invention reference is to be had to the accompanying drawings, constituting a part of this specification, in which similar characters of reference denote corresponding parts in all the views, and in which,

Figure 1 is a perspective view of the invention, showing it arranged as a single 50 bedstead.

Fig 2 is a vertical longitudinal sectional view taken through the bedstead showing it in double or extended formation.

Fig. 3 is a bottom plan view of the bed- 55 stead as illustrated in Fig. 1.

Fig. 4 is a vertical transverse sectional

view taken through the bedstead along the line 4—4 of Fig. 3.

Fig. 5 is a similar view showing the bed- 60 stead extended.

Fig. 6 is a horizontal sectional view showing the arrangement of the head or foot boards when the bedstead is in its single position and,

Fig. 7 is a similar view showing the ar- 65 rangement of the head or foot boards when the bedstead is in its extended or double position.

Referring more particularly to the views, the bedstead is shown in its single position 70 in Fig. 1 and is indicated in its entirety by the numeral 10, the main framework of the bedstead consisting essentially of the head and foot posts 11 and the side rails 12 which have their ends rigidly secured in the head 75

and foot posts. Secured to the inner faces of the side rails are strengthening ledges or elements 13 and coöperating with the side rail are horizontally disposed transversely extending cross pieces 14, two of the cross 80 pieces being extended from each side rail toward the other side rail with their free ends adapted to rest upon ledges 15 on the side rails when the bedstead is in its single position, the free ends of the cross pieces ex- 85

tended from one side rail, in this instance, being adapted to abut against the opposite side rail. It will also be noted that the cross pieces are arranged in pairs with the cross pieces of one pair disposed adjacent 90

the head end of the bedstead and spaced apart to extend relatively parallel in opposite directions while the cross pieces of the other pair are disposed adjacent the foot end of the bedstead and spaced apart to ex- 95

pend relatively parallel in opposite directions. The contiguous faces of the cross pieces in each pair are formed with grooves 16 substantially T-shaped in cross formation and interposed between the cross pieces 100 in each pair is a slide 17 having longitudinal T-shaped ledge portions 18 operating in the T-shaped grooves 16. To prevent relative displacement of the interfitting cross pieces and slides, stirrups 19 have their inner ends 105 secured to the slides in each instance, said stirrups projecting beneath the cross pieces and having their free ends turned up as at 20, the stirrups being secured to the under sides of the slides. Projecting pins 21 on 110 the outermost cross pieces in each set or pair are adapted to be engaged by the stir-

2 rups passing beneath the outermost cross pieces so as to limit the extensibility of the structure when the side rails are moved apart, causing the slides to operate upon the 5 cross pieces. Mounted to swing on the under side of each slide 17 for vertical swinging movement is a leg or post 22 which, when the bedstead is in single position is folded against the under side of its supporting slide, and rigidly secured to the under side of one of the cross pieces in each 10 pair, is an angular shaped bar 23 which has pivoted thereon a link 24, the other end of which is formed with a slot 25 through 15 which passes a pin 26 on a bearing 27 secured to the leg or post 22. With this arrangement it will be seen that when the bedstead is in its single position, the legs 22 will be folded up against the under sides 20 of the slides 17, as shown in Fig. 4, and referring to Fig. 5 it will be clearly seen that when the bedstead is extended the legs, through the medium of the link connection will be swung downwardly into supporting 25 position to insure proper support of the bedstead when it is extended.

30 A panel 28 in the nature of a board, is rigidly secured to one of the head posts and a similar panel is rigidly secured to one of 35 the foot posts with an auxiliary board 29 mounted to swing upon the board 28 as shown, the bedstead when in normal or single position having the auxiliary board 29 folded against the rigid board and lying 40 flush with the outer faces of the posts, whereas when the bedstead is extended the auxiliary board 29 is swung upon the rigid board to occupy the intervening space between the posts, and form an enlarged panel 45 coextensive with the new width of the extended bedstead. Pins 30, project from one of the head posts and foot posts and extend into openings 31 in the auxiliary board 29 when the bedstead is extended in order to insure securing the auxiliary board in rigid 50 position and in proper relation to the head or foot posts against which it abuts. If desired a suitable catch such as indicated at

55 32 may be employed to lock the auxiliary board in its open position when the bedstead is extended.

60 From the foregoing description it will therefore be seen that the bedstead described presents a strong and durable structure, and which as shown, when in single position will 65 present as neat and effective appearance as when it is in extended position, the operation of extending the bedstead or returning it from double to single position, being simple and easily accomplished.

65 Having described my invention, I claim:

1. An extensible bedstead, comprising in combination, laterally movable side portions, foldable head and foot boards secured to the opposite extremities of said side portions, interfitting cross pieces secured to 70 said side portions between said head and foot boards, means for preventing any accidental displacement of the cross pieces, auxiliary supporting legs hingedly connected with the under faces of said cross pieces 75 for horizontal swinging movement, and a slotted connection for pivotally associating the legs with certain of the cross pieces for causing an automatic vertical swinging movement of said legs upon the adjustment of the cross pieces.

2. An extensible bedstead comprising, in combination, laterally movable side portions, foldable head and foot boards secured to the opposite extremities of said side portions, interfitting cross pieces secured to 80 said side portions between said head and foot boards, auxiliary supporting legs connected with the under surfaces of certain 85 of said cross pieces, a bar carried by the under surface of one of said cross pieces, and means having a pivotal connection with the bar and legs for establishing an automatic operation of the legs upon the adjustment of said cross pieces.

85 In testimony whereof I affix my signature in presence of a witness.

90 ADRIAN ST. C. GARMAN.

Witness:

AMY B. HORN.
